UNITED STATES PATENT OFFICE.

HENRY P. LETART, OF WATERBURY, CONNECTICUT.

DRIFTING VALVE.

Application filed November 7, 1919. Serial No. 336,485.

To all whom it may concern:

Be it known that I, HENRY P. LETART, a citizen of the United States, residing at Waterbury, in the county of New Haven and 5 State of Connecticut, have invented certain new and useful Improvements in Drifting Valves, of which the following is a specification.

The present invention relates to improvements in drifting valves designed to supply 10 to the valve chest and locomotive cylinders during drifting or running with closed throttle a sufficient quantity of steam, laden with lubricant whereby to overcome or eliminate the vacuum produced by operation of 15 the pistons, the cooling of the cylinders by the suction of cool air thereinto and the carbonization of the cylinders which is resultant from the foregoing action.

20 To this end this new invention consists of the construction, combination and arrangement of parts to be hereinafter specifically described and claimed. Reference will now be had to the drawings forming a part of 25 this specification, wherein:

Figure 1 is a fragmentary view in elevation of a locomotive having my drifting valve applied thereto.

Figure 2 is a vertical sectional view 30 through my drifting valve, and through a locomotive cylinder and valve chest to which it is connected.

Figure 3 is a side elevation of the valve.

Figure 4 is a top plan view thereof.

35 Figure 5 is a horizontal sectional view taken on the line 5—5 of Figure 2, and

Figure 6 is a sectional view of the air inlet and strainer for the valve.

Throughout the following detail description 40 and on the several figures of the drawings, similar parts are referred to by like reference characters.

It should be understood that I may employ a drifting valve of my type for each 45 cylinder of the locomotive, but in the illustration herein set forth I have preferred to disclose a single drifting valve arrangement serving the two cylinders and in such an arrangement the drifting valve is preferably 50 disposed just in advance of the locomotive saddle 1 as shown in Figure 1. Referring to Figure 3, more particularly, the valve will be observed to comprise a casing or housing 2 having a removable cover plate 3 with a central opening therethrough designated 4. This opening is to atmosphere so as to ad-

mit atmospheric pressure into the valve casing and the opening is preferably provided with an inlet or strainer tube, shown most clearly in Figure 6 of the drawing, having 60 a threaded connection 5 and screened openings 6 at opposite ends. The casing 2 is placed in communication with the dome or turret of the locomotive by means of the auxiliary steam supply pipe 7 so as to furnish a supply of dry steam for distribution to the steam chests in the manner hereinafter specifically set forth. Opposite the connection of the pipe 7 to the casing 2, the latter is provided with a by-pass 8 communicating 70 with the interior of the casing through the opening 9 at the side and through the opening 10 at the bottom, this by-pass leading by way of the conduit 11 to the main steam or admission pipes 12 for the steam or valve 75 chests 13. Within the casing 2 is mounted the valve member proper which in this instance is provided with three separate spaced piston heads 14, 15, and 16, respectively, all of the same size and suitably mounted upon a common stem 17 in any desired mechanical manner. These piston heads are preferably provided with piston rings to prevent leakage of pressure as customary, but these details need not be more 85 specifically referred to. Beneath the valve member is arranged an expansion spring 18 which possesses just sufficient strength or tension to normally sustain the weight of the valve member without compression so 90 that said valve member will be held in its uppermost dotted lined position shown in Figure 3, which position I designate as the closed position, because in such position head 16 closes the pipe 7 and the entrance to the by-pass 8 so that no steam from the auxiliary 95 supply is permitted to enter the casing or pass to the valve chest therethrough. When, however, in the operation of this device the spring 18 is compressed by movement of 100 the valve member into the full lined position of Figure 3, said valve is in opened position, in which position the auxiliary steam supply will pass through the casing between the heads 15 and 16, the pressure of the said auxiliary supply being equally against the top side of the head 16 and the under side of the head 15.

The side of the casing 2 at a point intermediate the heads 14 and 15 of the valve 110 member is provided with an outlet 19 to permit the escape of any leakage of any pres-

sure which happens to pass the head 15 by virtue of worn rings.

The valve chest construction is of the conventional form employing a hollow piston 5 valve designated 20 and this portion of the locomotive construction does not require specific description.

In the use of this invention it will be understood that the valve under normal conditions is in its closed position with the valve member at its uppermost position. When the throttle of the locomotive is opened and steam supplied to the admission part of the valve chests through the pipes 12 the pressure is also present in the conduits 11 and will enter the bottom of the casing 2 through the port 10 into the spring chamber 10' where it will coact to maintain the valve member in closed position. While the engine is running, however, and when the throttle is closed, the reciprocation of the cylinder pistons, as is well known, produces a vacuum condition which acting through the valve chests tends to produce a vacuum 25 in the spring chamber 10' and necessarily in the conduits 11. The atmospheric pressure entering through the upper end of the casing at 4 becomes effective upon the head 14 which being greater than the tension of the spring 18 moves the valve member down 30 against its seat indicated at 21. The valve is now in open position so that the steam from the boiler will pass by the pipe 7 through the valve and bypass 8 to the valve 35 chests where the steam will maintain the temperature in the cylinders at a high point and will relieve the vacuum condition as well as supply the necessary lubrication. Upon opening of the throttle valve and the 40 introduction of pressure into the admission part of the valve chest, this pressure being greater by far than the atmospheric pressure upon the open end of the valve member will become effective against the lower 45 valve head 16 and in conjunction with the spring 18 will cause the valve member to resume its normal closed position. It will therefore be apparent that so long as pressure is present in the admission part of the 50 valve chest the drifting valve is closed whereas the vacuum condition in the valve chest during movement of the locomotive due to the action of the cylinder piston when the throttle is closed, in other words when 55 the locomotive is drifting, causes the valve to open and admit a limited quantity of live steam for lubricating the parts.

Having thus described my invention, what I claim as new is:

60 1. A drifting valve for locomotives, including a valve casing open at one end to the atmosphere, a valve member slidable within the casing and having a piston head at each end thereof, a conduit leading from the 65 lower end of the casing to the normal steam

supply of the locomotive whereby the pressure thereof acts upon the lower head to hold the valve in a closed position while the suction of the engine cylinder cooperates with the atmospheric pressure on the upper 70 piston head to move the valve into open position when the locomotive is running with the throttle closed, and means controlled by the movements of the valve member for supplying auxiliary steam to the steam chest 75 when the valve is in an open position.

2. The combination with the steam chest, its steam supply pipe, and the boiler of a locomotive, of a drifting valve comprising a casing, a piston valve therein having a 80 series of spaced heads, one end of said casing being open to the atmosphere to subject the outer face of one of said valve heads to atmospheric pressure, a conduit leading from the boiler and entering the 85 casing at one side thereof, a branch conduit leading from the steam supply pipe of the steam chest to the casing to admit pressure from the chest beneath a face of a second valve head when the engine is 90 running with the throttle open tending to hold said second head in position normally closing the boiler conduit entrance and to relieve pressure from said face when the engine is running with the throttle 95 closed, and a by-pass leading from the side of the casing to said branch conduit, said by-pass and branch conduit serving to convey auxiliary steam to the steam chest when the locomotive is running with the 100 throttle closed and the piston valve has been moved by atmospheric pressure acting upon the outer face of the first mentioned piston head to cause the second mentioned piston head to uncover the entrance from the casing to the boiler conduit.

3. The combination with the steam chest, its steam supply pipe and the boiler of a locomotive, of a drifting valve comprising a casing having an opening in the upper 110 end thereof, a piston valve therein provided with a series of piston heads the uppermost one of which is subject to atmospheric pressure through said opening, a conduit leading from the boiler to the side of the casing, a branch conduit leading from the lower end of the casing to the steam supply pipe, a by-pass leading from the side of the casing to the steam supply pipe through which auxiliary steam conveyed to the casing through the boiler conduit is adapted to pass to the steam chest, a second valve head in the lower end of said casing, and a spring between the second valve head and the lower end of the casing acting upon 115 said valve head in conjunction with the steam chest pressure in said branch conduit to cause said second valve head to occupy a position closing the boiler conduit and by-pass, said second valve head being auto- 120 125 130

matically shifted by the atmospheric pressure upon said first mentioned valve head to a position opening the boiler conduit and by-pass upon the reduction of pressure in 5 the steam chest when the engine is running with the throttle closed.

4. A drift valve for locomotives, including an upright valve casing having the upper end thereof open to the atmosphere, 10 a valve member slidable up and down within the casing and having a piston head at each end thereof, a spring normally supporting the valve member in a closed position, a conduit leading from the lower end 15 of the casing to a steam supply pipe of

the locomotive, whereby the normal steam pressure acts upon the lower piston head and cooperates with the spring to hold the valve in a closed position while the suction of the cylinder cooperates with the atmospheric pressure on the upper piston head to move the valve downwardly against the action of the spring when the locomotive is running with the throttle closed, and means controlled by the movements of the valve member for supplying auxiliary steam to the steam chest when the valve is in a lowered position. 20 25

In testimony whereof I affix my signature.
HENRY P. LETART.
